UNITED STATES PATENT OFFICE.

EARL HANCHETT, OF JAMESTOWN, PENNSYLVANIA.

BASKET.

1,057,483.

Specification of Letters Patent.

Patented Apr. 1, 1913.

Application filed August 5, 1911. Serial No. 642,479.

To all whom it may concern:

Be it known that I, EARL HANCHETT, a citizen of the United States, residing at Jamestown, in the county of Mercer and 5 State of Pennsylvania, have invented certain new and useful Improvements in Baskets, of which the following is a specification.

This invention relates to improvements in 10 baskets and particularly to a basket having its walls formed flat and rigid, so that the contents of the same will not be liable to be crushed.

An important object of this invention is 15 to provide a basket, which is strong, durable and easy to manufacture.

In the construction of my basket I provide metallic rods having oppositely faced sockets formed therein for receiving the 20 horizontal strips, whereby these strips are securely held in place in the same plane and the wall of the basket formed flat.

In the accompanying drawings forming a 25 part of this specification and in which like numerals are employed to designate like parts throughout the same, Figure 1 is a side view of the basket, Fig. 2 is a plan view of the same, and, Fig. 3 is a sectional view taken on line 3—3 of Fig. 1.

30 In the drawings wherein is illustrated a preferred embodiment of my invention, my basket is shown as being formed of upper and lower preferably rectangular frames 1 and 2, which are alike. These frames are 35 spaced, as shown, and connected at their corners by vertical posts 3, which may preferably be formed of metal.

The numeral 4 designates strips, which 40 form the bottom of the basket and are attached to the lower frame 2. The side and end walls of the basket are alike, so a detailed description of one will suffice for all.

Each wall of the basket is preferably 45 formed of horizontal splints or strips 5, having their ends connected with the posts 3. At proper spaced intervals are disposed metal rods or strips 6, having their upper and lower end portions extending respectively through the upper frame 1 and lower 50 frame 2. Each of these metal rods is screw-

threaded at its upper and lower ends for the reception of ferrule-nuts 7. Each of the metal rods 6 is bent throughout its length for forming oppositely faced sockets 8 and 9, occurring alternately. These sockets 8 55 and 9 are disposed in the same plane and snugly receive the splints or strips 5. These splints are thus held in the same plane and hence the wall of the basket is flat. Attention is called to the fact that the rods 6 are 60 relatively rigid, whereby the wall of the basket will not crush. The lower end of each rod 6 also extends through the strips 4, as shown. Attention is called to the fact that the rods 6 are alternately reversed, that 65 is to say the socket 8 of one rod is disposed upon one side of the splint or strip 5 and the socket 8 of the alternate rod is disposed upon the opposite side of the splint or strip 5. The same thing is true of the sockets 9 70 of one rod and the corresponding socket of the alternate rod.

The basket is preferably provided with handles 11 secured to the end strips of the upper frame 1 and any suitable form of 75 cover or lid (not shown) may be provided for the basket if desired.

Attention is called to the fact that the load placed upon the bottom strips 4 will be supported by the rods 6. The structure of 80 the basket may be tightened up by proper manipulation of the ferrule-nuts 7, tending to draw the upper and lower frames 1 and 2 together.

I wish it understood that the form of my 85 invention herewith shown and described is to be taken as a preferred example of the same and that certain changes in the shape, size and arrangement of parts may be resorted to without departing from the spirit 90 of the invention or the scope of the subjoined claim.

Having thus described my invention, I claim:—

A basket of the character described, comprising a plurality of connected separate upstanding walls, each wall comprising a plurality of stout rigid metal rods, each metal rod having its material bent at right angles at spaced intervals forming oppo- 100

sitely faced pockets disposed in the same vertical plane and having horizontal upper and lower holding shoulders, slats fitting within the pockets and held by said shoulders against vertical displacement, and frame strips attached to opposite ends of the metal rods.

In testimony whereof I affix my signature in presence of two witnesses.

EARL HANCHETT.

Witnesses:

MICHAEL LYNCH,
ROBERT BURNETT.
